KEY OPERATED CASH REGISTER

Arthur Henry Gledhill, Halifax, England

Application June 13, 1932, Serial No. 616,989, and
in Great Britain June 22, 1931

3 Claims. (Cl. 235—15)

This invention relates to a key operated cash register in which means are provided whereby a key or keys can be latched on to a common coupler so that when any other key is pressed the latched key or keys will also be depressed and so avoid the necessity for the operator to make long or difficult stretches when depressing two distantly spaced keys with one hand and enable a person with a small hand to operate the machine with ease. It has been proposed to effect this latching through mechanism actuated by a partial depression of a key or keys but in this arrangement if a key is depressed beyond the amount required to effect the latching, all the other keys become locked and a correct sale which involves the depression of a number of keys cannot be registered at that operation. Another disadvantage of this arrangement is that on the return stroke of the keys it is possible to uncouple one or more keys before the common key coupler reaches the end of its stroke, so as to throw the machine into an inoperative condition.

The present invention has for its object to introduce an improved method of effecting the aforesaid latching which will be simple in construction, positive in action and be free from the above mentioned disadvantages.

According to this invention any or every key of the cash register is so constructed or mounted that it can be displaced in relation to its axis to cause the key to engage the common key coupler so that when another key is depressed the key or keys so coupled are also depressed. The mechanism is so designed that the coupler during its upward movement automatically restores any of the keys which have been so displaced to the normal position.

In the accompanying drawings:—

Fig. 1 is a section showing two rows of keys in a normal position in relation to the common key coupler, and

Fig. 2 is a similar view showing one of the keys displaced to engage the common key coupler, and

Fig. 3 shows such key returned to its normal or inward position by the upward movement of the key coupler.

A indicates the keys, A¹ a displaced key and B the coupler.

In the example shown for latching the keys to

the key coupler any or every key of the register is formed with a short slot a for the passage of the key supporting shaft a¹ so that any or every key can receive the aforesaid displacement in relation to its axis, which may be effected for example by moving the key slightly forward. Pivoted to the key below the key supporting shaft is a forked plate a² which embraces the shaft a¹ and has two notches a³, a⁴ formed on one edge to engage a spring pressed pivoted detent a⁵ which maintains the key in either its normal or its displaced position. When the key is pulled forward the plate a² is turned by contact with the stationary shaft a to cause the notch a⁴ to engage the detent a⁵ and when the key is pushed back the plate is turned to cause the notch a³ to engage the detent a⁵. When the key occupies its displaced position as shown at A¹ the usual slot a⁶ in the rear end of the key engages the common key coupler. Due to the position of the centres of the common key coupler B and of the key supporting shaft a¹, the movement of the coupler during its upward stroke automatically returns any key occupying a displaced position to its normal position by the engagement of the coupler with the end of the slot a⁶ as shown in Fig. 3. By the invention described any key which may have been latched in error can be unlatched without having to complete a transaction providing such unlatching is done before any key is depressed, but on the keys being depressed all the keys are united to the coupler for the full downward and upward stroke, and cannot be disengaged from the coupler until the latter has performed all the functions for which it is designed.

What I claim as my invention and desire to secure by Letters Patent in the United States is:—

1. In a key operated cash register or the like, the combination of keys each having a slot for a common key supporting shaft, a key coupler for coupling engagement with the rear ends of the keys, a pivoted member carried by each key and associated with said common shaft for movement thereby, a second pivoted member arranged adjacent said first mentioned pivoted member and carried by each key, and means carried by said pivoted members for retaining the key in a forward or rearward position.
2. In a key operated cash register, the combination of keys having a slot for a common key

supporting shaft, a key coupler adapted to be engaged by slots in the rear ends of the keys, a member pivoted to each key below the common shaft and adapted to be moved thereby, said member having notches on one side thereof, and a pivoted detent member arranged adjacent said notched member and adapted to engage said notch member whereby the key may be retained in a forward or rearward position when moved 10 in a corresponding position.

3. In a key operated cash register, the combi-

nation of keys each having a slot for a common key supporting shaft, a key coupler adapted to be engaged by slots in the rear ends of the keys, a forked plate pivoted to each key below the common shaft and arranged to embrace the latter, the said forked plate having two notches formed in one edge, and a spring pressed detent adapted to engage one or other of said notches when the key is moved forward or backwards and retain it in its forward, or rearward position.
